ABSTRACT

A flyback EHT- and sawtoothcurrent-generator using a transformer and switching means connected thereto which conduct during a scan period and do not conduct during a flyback period, and partly parasitic reactances connected to the transformer. During the flyback period the generator has at least two resonant frequencies so chosen that a substantially oscillation-free scan is produced and during the scan it has at least one resonant frequency which is approximately equal to an integral multiple of the reciprocal value of the duration of the scan period.

FLYBACK EHT AND SAWTOOTH CURRENT GENERATOR

The invention relates to a flyback EHT- and sawtooth current generator particularly for television display apparatus, including switching means which are periodically non-conducting during a flyback period τ are conducting during a scan period $T - \tau$ and a network having input terminals connected to the switching means, said network comprising a transformer having at least one primary winding and possibly one or more coils connected thereto through which said sawtooth current flows during the scan period, and a secondary winding to which a rectifier circuit is connected for generating said EHT from the voltage pulses occurring during the flyback period at the secondary winding, said network, due to the leakage inductance present between the transformer windings having a first resonant frequency f_α during the flyback period which frequency is substantially equal to the expression:

$$K/(2\tau) \left\{ 1 + (4/\pi^2 K^2) \tau/(T - \tau) [1 - \frac{2}{3} S] \right\}$$

in which $K = 1$ and S is a correction factor which is equal to the relative reduction of the slope of the sawtooth current at the end of the scan period relative to this slope at the centre of the scan period, and a second resonant frequency f_ν which is substantially equal to the said expression for K is equal to an odd integer of more than 1.

It is known from the Netherlands Patent Specification 88020 and from the book "Televisie by P. Kerkhof and W. Werner," third edition, chapter XIII to use a transformer having one or more primary windings and a secondary winding in flyback EHT- and sawtooth-current-generators for television display apparatus and to proportion the impedances of the circuit elements present, such as the transformer windings, the leakage inductance between the primary windings and the secondary winding, the inductances of coils which are generally connected to the primary winding as well as the parasitic and non-parasitic capacitances, in such a manner that hardly any or no free oscillations occur in the secondary voltage during the scan period. Such free oscillations have the drawbacks that useful energy is lost, that this useless energy is mainly dissipated in the transformer so that overheating of the transformer may occur and that the switching means conducting during the scan period may become prematurely non-conducting in case of large free oscillations.

The above-mentioned literature shows that said circuit constitutes a 4th-order network during the flyback period with two resonant frequencies and that the said free oscillations may be maintained low by proportioning the circuit elements in such a manner that these two resonant frequencies f_α and f_ν have very defined values which are dependent on the duration of the flyback period τ and the duration of the scan period $T - \tau$. As is apparent from the expression given in the preamble, the optimum value of f_α and f_ν is also slightly dependent on the extent to which the slope of the sawtooth current flowing through the deflection coils varies when the so-called S-correction of this current is used.

Theoretically a scan period completely without oscillations can be obtained by exact proportioning of f_α and f_ν in a flyback EHT and sawtooth current generator. However, as a result of inevitable interfering influ-

ences, this cannot be achieved in practice. These interfering influences are, *inter alia*:

1. The presence of parasitic reactances in the network which are so small on the one hand that they can no longer be controlled but are on the other hand sufficiently large to make a scan without oscillations impossible.

2. The presence of losses in the network during the flyback period. An essential part thereof is constituted by useful energy which is derived through the rectifier.

3. Tolerances in components and production spread which make it impossible to render the frequencies f_α and f_ν sufficiently accurately equal to values which are necessary for a scan without oscillations.

An object of the invention is to provide a proportioning measure with which in spite of the said interfering influences the occurring scan oscillations can be maintained very small and to this end the flyback EHT and sawtooth current generator according to the invention is characterized in that said network has a frequency f_β located between f_α and f_ν at which the impedance of the network at the input terminals is at a minimum, said frequency f_β being substantially equal to an integral multiple of the reciprocal value of the duration of the scan period.

The said network has a certain resonant frequency f_β located between the two parallel resonant frequencies f_α and f_ν at which the impedance of the network at the input terminals is at a minimum (equal to zero in cases of a network which is completely without losses). This is actually the resonant frequency of the generator during the scan period, hence with conducting switching means. It is known that for an exact tuning of the flyback EHT generator to a scan which is without oscillations only the parallel resonant frequencies f_α and f_ν are important and that the series resonant frequency f_β is irrelevant. The location of f_β has only influence on the shape of the flyback pulse occurring across the input terminals of the network.

The invention is based on the recognition of the fact that the value of the frequency f_β has also a very great influence on the amplitude of the scan oscillations still remaining as a result of the said interfering influences and that this amplitude is at a minimum if the value of f_β is substantially equal to an integral multiple of the reciprocal value of the duration of the scan period.

A generator of this kind is preferably designed in such a manner that the quality of the generator during the scan period is more than 25 at the said frequency f_β .

The Applicant's pending Patent application No. 245,144, filed Apr. 18, 1972 describes flyback EHT- and sawtoothcurrent-generators in which the flyback network has at least three resonant frequencies f_α , f_ϵ and f_σ or more. A scan which is substantially without oscillations can also be achieved by rendering each of these resonant frequencies at least substantially equal to the given expression:

$$K/2 \tau \left\{ 1 + 4/\pi^2 K^2 \right\} \tau/T - \tau (1 - \frac{2}{3} S)$$

in which K is an odd positive integer, for example, 1, 3, 5, respectively, or 1, 5, 7 respectively. In such a case the network has a first series resonant frequency f_{β_1} between f_α and f_ϵ at which the input impedance of the network is at a minimum and a second series resonant frequency f_{β_2} between f_ϵ and f_σ at which

the input impedance of the network is at a minimum. f_{β_1} and f_{β_2} are also the frequencies at which the network resonates during the scan period.

As a result of the said interfering influences the scan will not be completely without oscillations even in a flyback EHT generator of this kind. The oscillations which then occur generally comprise two components, one of the frequency f_{β_1} and one of the frequency f_{β_2} .

It is found that independent of each other for a minimum amplitude of the f_{β_1} component the frequency f_{β_1} is to be chosen optimum, that is to say, approximately equal to an integral multiple of the reciprocal value of the duration of the scan period and for a minimum amplitude of the f_{β_2} component the frequency f_{β_2} must be approximately equal to an integral multiple of the reciprocal value of the duration of the scan period.

On the other hand it is, however, found that the component of the lowest frequency generally has a considerably larger amplitude than the component of the higher frequency. For a flyback EHT and sawtooth current generator in which the said network has a third resonant frequency f_{ϵ} between f_{α} and f_{β_2} during the flyback period which resonant frequency is at least substantially equal to the given expression for K being equal to an odd integer, a considerable reduction of the scan oscillations is thus already achieved if the frequency f_{β_1} between f_{α} and f_{ϵ} at which the impedance of the network at the input terminals is at a minimum is substantially equal to an integral multiple of the reciprocal value of the duration of the scan period.

As noted hereinbefore an optimum proportioning is achieved when the said frequency f_{β_2} between f_{ϵ} and f_{β_2} at which the impedance of the network at the input terminals is at a minimum is also substantially equal to an integral multiple of the reciprocal value of the duration of the scan period.

The invention will be further described with reference to the Figures shown in the drawings. In these drawings:

FIG. 1 shows a first embodiment of a flyback EHT- and sawtoothcurrent-generator for which the invention can be used.

FIG. 2 shows the equivalent circuit diagram of the embodiment of FIG. 1.

FIG. 3 shows a diagram to explain the present invention.

FIG. 4 shows a second embodiment of a flyback EHT- and sawtoothcurrent-generator for which the invention can be used and

FIG. 5 shows the equivalent circuit diagram of the embodiment of FIG. 4.

The embodiment of FIG. 1 shows a transformer 1 having a primary winding 2, one or more auxiliary windings 3 rigidly coupled to the primary winding, and a secondary winding 4. A tap 6 on the primary winding is connected to the positive terminal of a voltage supply source 7 the negative terminal of which is connected to ground. The series arrangement of a plurality of deflection coils 9, a linearity corrector 10 and an S-correction capacitor 11 is arranged between a second tap 8 and the lower end of the primary winding. The tap 8 and the lower end of the primary winding are located symmetrically relative to the tap 6 so that this series arrangement is fed symmetrically relative to ground.

A transistor 12 operating as a switch is provided between the upper end of the primary winding and ground and a capacitor 13 is connected in parallel with this transistor. Said secondary winding 4 is connected to ground at one end and at the other end to a rectifier circuit consisting of a rectifier 14 and a smoothing capacitor 15; the EHT generated by the rectifier is applied to the acceleration anode of a television display tube not further shown.

- 10 Switching pulses which periodically cut off the transistor 12 at the end of each scan period are applied between the base and emitter of transistor 12 through a separating transformer 18, a series inductance 19 and a parallel diode 20. The transistor 12 is a so-called slow 15 switching transistor and the elements 19 and 20 are included so as to accelerate the switching off of the transistor at the end of the scan period.

FIG. 2 shows the simplified equivalent circuit diagram of the circuit of FIG. 1. In this diagram E denotes the voltage source 7, SW denotes the switch constituted by transistor 12 and diode 20. C_1 is the capacitance of the capacitor 13 increased by the collector emitter capacitance of the transistor and the transformed parasitic capacitances of the primary winding, 25 the auxiliary windings, the deflection coils and the linearity corrector. L_1 is the inductance of the primary winding and the deflection coils and the linearity corrector connected thereto, all transformed to the terminals to which the switch is connected. L_2 is the leakage inductance between secondary and primary windings and C_2 is the parasitic capacitance of the secondary winding and the input capacitance of the rectifier circuit likewise transformed to the terminals to which the switch is connected.

During the scan period switch SW is closed. The voltage E from the voltage supply source 7 is therefore present across capacitor C_1 and also across inductor L_1 . As a result, a (sawtooth) current linearly varying with time will flow through the inductor L_1 . When, as a result of a pulse applied to the base electrode of transistor 12, switch SW is rendered non-conducting, free oscillations will occur in the network as a result of the magnetic energy present in L_1 . These oscillations produce pulsatory voltages V_1 and V_2 , the so-called flyback pulses across capacitors C_1 and C_2 , respectively. As soon as the flyback pulse across C_1 decreases to the value of the supply voltage $-E$, that is to say, as soon as the collector potential of transistor 12 becomes negative relative to ground, the collector-base pn-junction 35 of the transistor is in the forward direction and the next scan period commences. Switch SW in the equivalent circuit diagram of FIG. 2 therefore closes automatically 40 as soon as the flyback voltage present across this switch becomes equal to zero.

It is to be noted that the sawtooth current in the circuit diagram of FIG. 1 flows during the first part of the scan period through the diode 20, the base-collector junction of the transistor and subsequently through the transformer and the deflection coils to the voltage supply source and thus feeds back energy to the voltage supply source. Some time after the commencement of the scan period the base-emitter junction of the transistor is rendered conducting by means of the pulses applied to the base electrode of the transistor so that during the second part of the flyback period the sawtooth current now reversed in polarity can flow from the voltage supply source through the transformer and the de-

flection coils and subsequently through the collector electrode and the emitter electrode of the transistor to ground; then the voltage supply source supplies energy to the network.

It is to be ensured that during the scan period only a sawtooth current flows through L1 and that free oscillations do not occur as a result of electrical or magnetic energy present in the inductor L2 and capacitor C2. Such a scan period without oscillations is obtained if it is ensured that the current flowing through L2 is equal to zero during the entire scan period and therefore also at the commencement and the end of the flyback period and that the voltages across C2 is equal to the battery voltage $-E$.

To satisfy this condition the following two relations are to apply for each resonant frequency α of the flyback period network, thus of the network in case of an open switch SW.

$$\alpha\tau = K\tau + 2\phi\alpha \quad (I)$$

$$\alpha\tan\phi\alpha = (i'_o)/i_o \quad (II)$$

In these relations τ is the duration of the flyback period, K is an odd integer, i_o is the value of the sawtooth current at the commencement of the flyback period i'_o is the derivative with time of this current at the commencement of the flyback period and $\phi\alpha$ is a phase angle. It is possible to eliminate $\phi\alpha$ from the two equations. Then a power series in $\tau i'_o/i_o$ is produced for $\alpha\tau$. If this series is limited to the first two terms it is found that:

$$\alpha\tau = K\tau + (2/K^2)(\tau i'_o/i_o)$$

When a purely linear sawtooth current flows through L1 and hence through the deflection coils, there applies as an approximation:

$\pi(i'_o/i_o) = (2\tau)/(T-\tau)$ in which $T-\tau$ is the duration of the scan period. When, however, the deflection current has a slightly S-shaped character as a result of the S-correction capacitor of FIG. 1 which is left out of consideration in the equivalent circuit diagram of FIG. 2, which character is conventional in television display apparatus, there applies as an approximation:

$$(\tau i')i_o = (2\tau/T - \tau)(1 - \frac{3}{8}S)$$

in which S is the relative reduction of the slope of the deflection current at the end of the scan period relative to this slope in the centre of the scan period. The above-mentioned condition for $\alpha\tau$ then changes to:

$$\alpha\tau = K\pi \left\{ 1 + 4/(K^2\pi^2) \tau/(T-\tau) (2 - \frac{3}{8}S) \right\}$$

with $\phi\alpha = \alpha/2$, there follows:

$$\alpha = (K/2\pi) \left\{ 1 + 4/(K^2\pi^2) \tau/T - \tau (1 - \frac{3}{8}S) \right\} \quad (III)$$

as already noted hereinbefore the equations (I) and (II) and hence also equation (III) must apply to each resonant frequency of the flyback network in order to obtain a scan without oscillations.

The network of FIG. 2 has two resonant frequencies $\alpha = 2\pi f_\alpha$ and $\gamma = 2\pi f_\gamma$ during the flyback period namely:

$$\alpha^2 = \frac{1}{2} \left\{ \frac{1}{L_1 C_1} + \frac{1}{L_2 C_2} + \frac{1}{L_2 C_1} \right\}$$

$$\gamma^2 = \sqrt{\frac{1}{4} \left(\frac{1}{L_1 C_1} + \frac{1}{L_2 C_2} + \frac{1}{L_2 C_1} \right)^2 - \frac{1}{L_1 L_2 C_1 C_2}}$$

and to obtain a scan without oscillations the network is proportioned in such a manner that f_α satisfies equation (III) for $K = 1$ and also f_γ satisfies equation (III), for example, $K = 3$ or $K = 5$, etc.

In addition to the frequencies f_α and f_γ the network has a third characteristic frequency f_β i.e. the frequency located between f_α and f_γ at which the input impedance of the network is at a minimum (zero). For the network of FIG. 2 this is the series resonant frequency of L2 and C2, thus $\beta^2 = (2\pi f_\beta)^2 = (1/L_2 C_2)$. At a given period of T and at a previously chosen flyback period of τ the values of f_α and f_γ are laid down by the condition given in equation (III). The value f_β may however, be freely chosen between f_α and f_γ .

It is known that for values f_α and f_γ determined in accordance with equation (III) the value of f_β determines the shape of the flyback pulse occurring across the input terminals of the network. This is further shown in FIG. 3 by the curves denoted by V1 which are found for different values of f_β . As this Figure shows, the voltage V1 decreases for low values of f_β before the termination of the flyback period to below the value of the battery voltage. In order to prevent this, f_β is generally chosen to be sufficiently large and particularly f_β is located in the region $\sqrt{f_\alpha} f_\gamma < f_\beta < f_\gamma$. It will be evident that if f_β is chosen to be in the region $f_\alpha < f_\beta < \sqrt{f_\alpha} f_\gamma$ switching means are to be used in the flyback EHT and sawtooth current generator in such a manner that they do not conduct before the termination of the previously determined flyback period τ .

It has been found that the location of the frequency f_β has also a considerable influence on the amplitude of the oscillations occurring during the scan period which oscillations are produced because a scan period which is completely without oscillations cannot be achieved due to the interfering influences described in the preamble. This is further shown in FIG. 3 by the curve ER. This curve shows as a function of f_β the ratio between the energy which gives rise to the said unwanted oscillation during the scan period and the total electromagnetic energy during the flyback period in the network. It is clearly shown that this energy ratio at given values of f_β has maximum values and has minimum values at values located therebetween.

It has been found that the maximum values in the ER curve occur at values of f_β for which there applies

50

$$\pi f_\beta (T-\tau) = \tan(\pi f_\beta (T-\tau))$$

However, since $\pi f_\beta (T-\tau)$ is large relative to 1 it may be assumed that said maximum values occur approximately at

60

$$\tan(\pi f_\beta (T-\tau)) \rightarrow \infty$$

This is the case if $f_\beta (T-\tau) = n + \frac{1}{2}$ ($n = \text{integer}$). The minimum values located between the maximum values occur at those values of f_β for which there applies that $f_\beta (T-\tau) = n$, thus $f_\beta = n/(T-\tau)$.

The curve of FIG. 3 is determined for a flyback EHT and sawtooth current generator in which f_α satisfies equation (III) for $K = 1$ and f_γ for $K = 3$ (third harmonic tuning) and for a flyback ratio of $\tau/T = 0.15$. FIG. 3 shows the values of n associated with the various minimum values. It is found that in order to obtain both

a satisfactory shape of the primary flyback pulse and a minimum amplitude of the scan oscillations, n is preferably chosen to be equal to 7 in this case.

It will be evident that the above given proportioning of f_β yields two important advantages.

1. For a given nature and magnitude of the said interfering influence which make an exact tuning of the generator impossible, the amplitude of the scan oscillations caused thereby is maintained as small as possible. In other words, for a given admitted amplitude of the scan oscillations, considerably larger deviations of f_α and f_β relative to their exact tuning value can be admitted.

2. The spread of f_β caused by tolerances and production spread in the different species of one and the same production series do not substantially have any influence on the amplitude of the scan oscillations which is in contrast with the fact when f_β is located, for example, in the middle between a maximum and a minimum value, for example, $f_\beta = (n - \frac{1}{4}T - \tau)$. Production spreads in f_β will then have a large influence on the amplitude of the scan oscillations.

It is to be noted that the curve denoted by ER in FIG. 3 is determined for a network which in case of a closed switch has a given quantity of resistive losses in the oscillatory circuit constituted by E, SW, L2, C2 (quality factor Q is approximately equal to 20). It is found that when reducing these losses the maximum values of the ER-curve increase and the minimum values decrease. By reduction of the resistive losses, particularly by reduction of the copper and iron losses in the transformer 1 a further reduction of the scan oscillations can be obtained for the above-mentioned optimum proportioning of f_β . In case of an f_β not proportioned in an optimum manner such a step results in an increase of the scan oscillation.

In order to obtain an optimum use of the correct proportioning of f_β the quality factor Q of the scan circuit is therefore preferably chosen to be larger than 25. In case of a correct proportioning of f_β in combination with a Q of 25 an oscillation energy ratio (ER) of only approximately $\frac{1}{2}$ percent is found for a relatively large (5 percent) deviation of the ratio f_β/f_α relative to the optimum value of this ratio. This quality factor can be simply determined from the exponential decrease of the scan oscillations during the scan period.

The maximum values in the ER curve located on either side of a minimum $n/(T - \tau)$ are located at approximately $f_\beta = (n - \frac{1}{2}T - \tau)$ and $(n - \frac{1}{2}T - \tau)$. The distance between a minimum and an adjacent maximum thus is $\frac{1}{2}(T - \tau)$. Furthermore FIG. 3 shows that f_β must deviate not more than approximately $\pm\frac{1}{6} 1/(T - \tau)$ from the optimum $n/(T - \tau)$ so as to be located to a sufficient extent in a minimum value of the ER curve. For television display apparatus in which $T - \tau$ may be approximately 55 μ sec the admissible deviation of f_β is thus approximately ± 2.3 kHz. It follows from the above that for f_β an absolute accuracy (in kHz) and not a relative accuracy (in percent) is required.

In the embodiment of FIG. 4 corresponding elements have the same reference numerals as those in FIG. 1. As compared with the embodiment of FIG. 1, FIG. 4 shows an additional transformer winding 5 which is connected with one side to the positive terminal of the voltage supply source 7 and with the other side through a parallel LC circuit 16, 17 to the collector electrode

of transistor 12. The equivalent circuit diagram is shown in FIG. 5. In this diagram L3 and C3 mainly represent the inductance of coil 16 and the capacitance of capacitor 17 while L4 is the leakage inductance between the windings 4 and 5. As already explained in said pending patent application the network of FIG. 5 has three resonant frequencies a_α , f_ϵ and f_β and a substantially oscillation free scan period can be obtained by choosing these frequencies in such a manner that all three of them satisfy equation (III) for K is an odd integer, for example K is equal to 1, 5 and 7, respectively.

In this case the network has two frequencies f_{β_1} and f_{β_2} at which the input impedance of the network is at a minimum (zero) and the first (f_{β_1}) of which is located between f_α and f_ϵ and the second (f_{β_2}) of which is located between f_ϵ and f_γ . Due to the interfering influences referred to in the preamble some oscillations will also occur during the scan period in this case. These oscillations will consist of a first component of the frequency f_{β_1} and a second component of the frequency f_{β_2} .

By choosing f_{β_1} within the given limits $[\pm\frac{1}{8}, 1/(T - \tau)]$ to be equal to an integral multiple of the reciprocal value of the duration of the scan period ($n/T - \tau$ with n an integer) the amplitude of the said first component can be adjusted at a minimum and likewise the amplitude of the said second component can be adjusted at a minimum by choosing f_{β_2} within the given limits $[\pm\frac{1}{8}(1/T - \tau)]$ to be equal to an integral multiple of the reciprocal value of the duration of the scan period ($m/T - \tau$ with m an integer).

It is to be noted that in the equivalent circuit diagram of FIG. 5 an increase of f_{β_1} in case of an equal location of the other frequencies can be realized by reducing L3 and L4 and by increasing C1 and C3 and a slight adaptation of the other elements. An increase of f_{β_2} may be realized by reducing C3 and increasing C1 with a slight adaptation of the other elements.

What is claimed is:

1. A circuit for generating a sawtooth waveform comprising switching means periodically nonconducting during a flyback period and conducting during a scan period, a network means for establishing a plurality of resonant frequencies having a pair of input terminals coupled to said switching means, said network means

comprising a transformer having a primary winding coupled to said switching means and at least one secondary winding, whereby a leakage inductance exists between said windings, said network having a first resonant frequency during said flyback period substantially equal to the expression

$$K/2\tau [1 + (4/\pi^2 K^2 \cdot \tau/(T - \tau) (1 - 2S/3))],$$

wherein $K = 1$, $S = a$ correction factor substantially equal to the relative reduction of the slope of the sawtooth waveform at the end of the scan period relative to said slope in the middle of said scan period, $\tau =$ said flyback period, $T - \tau =$ said scan period, said network having a second resonant frequency substantially equal to said expression wherein K is an odd integer greater than one, said network having a third resonant frequency between said first and second resonant frequencies at which the impedance at said input terminals is a minimum, said third resonant frequency being sub-

stantially equal to an integral multiple of the reciprocal of the scan period.

2. A circuit as claimed in claim 1 wherein said network has a quality factor greater than twenty five at said third frequency during said scan period.

3. A circuit as claimed in claim 1 wherein said network further comprises means for establishing a fourth resonant frequency between said first frequency and said second frequency and being substantially equal to said expression for K equal to an odd integer.

4. A circuit as claimed in claim 3 wherein said network further comprises means for establishing a fifth resonant frequency between said fourth and second frequencies at which the impedance at said terminals is

a minimum, said fifth frequency being substantially equal to an integral multiple of the reciprocal of scan period.

5. A circuit as claimed in claim 1 further comprising rectifier means coupled to said secondary winding for providing a high voltage.

6. A circuit as claimed in claim 1 further comprising a deflection coil coupled to said primary winding.

7. A circuit as claimed in claim 1 wherein said transformer further comprises an additional winding, and said circuit further comprises a parallel tuned trap coupled between said additional winding and said switch.
